Fred. W. Smith.

INVENTOR:

John C. Howe,
by John C. Dewey,
Attorney.

UNITED STATES PATENT OFFICE.

JOHN C. HOWE, OF WORCESTER, MASSACHUSETTS, ASSIGNOR TO SULLIVAN FOREHAND, OF SAME PLACE.

REVOLVER.

SPECIFICATION forming part of Letters Patent No. 353,948, dated December 7, 1886.

Application filed July 31, 1886. Serial No. 209,662. (No model.)

To all whom it may concern:

Be it known that I, JOHN C. HOWE, a citizen of the United States, residing at Worcester, in the county of Worcester and State of Massachusetts, have invented certain new and useful Improvements in Revolving Fire-Arms; and I do hereby declare that the following is a full, clear, and exact description thereof, which, in connection with the drawings making a part 10 of this specification, will enable others skilled in the art to which my invention belongs to make and use the same.

My invention relates to revolving fire-arms, and to that class of fire-arms in which the barrel portion, provided with a revolving cylinder, and a shell-extractor, and actuating-spring, of any usual and ordinary construction, is hinged to the stock portion or handle of the fire-arm. By simply tilting the barrel portion upon the 15 stock the shell-extractor is automatically forced out to eject the shells, and returned to its first position to allow of the reloading of the cylinder.

My invention consists in certain novel features of construction and operation of the extractor lifter or disk located at the hinge of the fire-arm and adapted to automatically force out the shell-extractor by tilting the barrel portion upon the stock, and after the extractor is forced out to its farthest extent by 20 tilting the barrel portion as far as possible upon the stock, to cause the extractor and also the extractor-lifter to be automatically returned to their first positions by means of the actuating-spring encircling the stem of the extractor in the usual manner.

Referring to the drawings, Figure 1 represents a side elevation, partly in section, of a well-known form of revolver with my invention applied thereto, the barrel portion, shown 25 in section, being partially tilted on the stock preparatory to forcing out the shell-extractor. Fig. 2 represents the barrel portion shown in Fig. 1, the stock being broken off, tilted to its farthest extent on the stock, the shell-extractor, and extractor-lifter being returned to their first positions. Fig. 3 represents a cross-section, taken on line *x*, Fig. 1, through the point where the barrel portion is hinged to the stock, 30 looking in the direction of the arrow, same

figure. Figs. 4 and 5 represent the two parts of my improved extractor-lifter detached from each other.

In the accompanying drawings, the part marked A is the stock of a revolver of any 55 ordinary construction, having a shoulder, *a*, formed upon its outer lower end.

B is the barrel portion, connected with the stock A by means of a hinged joint of the usual construction, which allows the barrel portion B 60 to be tilted upon the stock A. Two ears, *a'* *a'*, formed upon the part B, extend between two ears, *b'* *b'*, formed upon the stock A, and a hinge pin or screw, *c*, extends through holes in said ears and screws into a threaded hole in 65 one of the ears, *b'*, on the stock A, all in the usual manner. A shoulder, *b*, is formed upon the lower part of the barrel portion B.

Upon the barrel portion B is supported in any ordinary manner the revolving cylinder 70 C, provided with a shell-extractor, D, secured upon the end of the stem *d*, which is encircled by a spiral spring, *e*, within the cylinder C, of the usual construction, for acting on the extractor D, to draw the extractor back into the 75 cylinder C at the proper time, all in the usual manner.

My extractor-lifter E is located at the hinge-joint, between the ears *a'* *a'* of the barrel portion B, and is held in place by and turns loosely 80 upon the hinge-screw *c*.

The extractor-lifter E consists of a circular metal disk provided with a finger, *g*, extending out from the edge thereof to engage with the inner end of the stem *d* of the extractor D, 85 in the usual manner. A circular groove, *h*, is cut or countersunk in one side of the lifter E, as shown in Fig. 4, adapted to receive, and in which is fitted an actuating-spring, G, as shown in Figs. 1 and 2, the top edge thereof being 90 flush with the surface of the disk E. One end of the spring G is enlarged or provided with the projection *i*, which fits into an opening, *j*, cut in the disk E in such a manner that the outer end, *i'*, will project out slightly beyond 95 the edge of the disk, forced out by the action of the spring G, as shown in Fig. 1. The groove *h* is made sufficiently wide to allow of the projection *i* being forced in against the action of the spring G, so that the end *i'* will be flush with 100

the edge of the disk E, as shown in Fig. 2. A hole, k, extends through the center of the lifter E, through which the hinge-pin e extends, and upon which pin the extractor has its bearing, 5 and turns when the barrel portion B is tilted upon the stock A.

The operation of my improved extractor-lifter E is very simple, and will be readily understood from the above description, in connection with the drawings.

The extractor E, with the spring G fitted therein, having the projecting end i' extending out beyond the surface of the edge thereof, is secured in the hinge-joint by means of the hinge-pin e, as shown in Fig. 1, with the finger g pressing against the end of the stem d of the extractor D. By tilting the barrel portion B upon the stock A the projecting end i' of the enlarged end of the spring G will come in contact with the shoulder a on the stock A, (see Fig. 1,) thus holding the extractor-lifter E, and preventing it from turning on the hinge-pin e, causing the extractor D to be forced out by the finger g pressing against the stem d. 25 By continuing to tilt the barrel portion B upon the stock A the shoulder b upon the barrel portion will come in contact with the sloping surface of the projecting end i' of the spring G, and force said projecting end within the opening j and groove h, and out of contact with the shoulder a on the stock A, thus allowing the lifter E to turn upon the pin e, and automatically releasing the extractor D, which is then drawn back into the cylinder C by means 30 of the actuating-spring e, of the usual construction and operation. The backward movement of the extractor D and its stem d causes the lifter E to return to its original position, all as shown in Fig. 2.

40 It will be readily seen that my extractor-lifter is very simple in its construction and operation and not liable to get out of order, consisting simply of a circular disk provided with a finger and a circular groove or channel cut 45 in one side thereof, and an opening at one edge thereof, extending between the edge and the circular groove, to receive the enlarged end of the spring G. The actuating-spring G, with one end enlarged, is easily made and 50 readily inserted in the groove in the disk E

by compressing the spring slightly, the natural expansion of the spring holding it in place, and the enlarged end i thereof in the opening j, with the end i' projecting out beyond the edge of the disk to furnish a bearing, against which the shoulder on the under side of the stock presses to prevent the disk from turning as the barrel is tilted, until at the proper time the shoulder on the barrel portion forces the projecting end of the spring G within the 60 edge of the disk and automatically releases said disk and the shell-extractor, allowing the same to be operated by the actuating-spring encircling the stem of the extractor D.

The projection i or enlarged end of the spring 65 G may be made separate therefrom and connected therewith, or be made a part thereof, as shown.

Having thus described my invention, what I claim as new, and desire to secure by Letters 70 Patent, is—

1. The combination, with the shell-extractor of a fire-arm and its actuating-spring, of the pivoted extractor-lifter E, located at the joint of the fire-arm, and an actuating-spring, G, 75 contained within the lifter and having one end enlarged and projecting beyond the edge thereof, and adapted to engage with shoulders on the barrel portion and the stock to automatically operate the shell-extractor by tilting the 80 barrel upon its hinge, in the manner substantially as shown and described.

2. In a revolving fire-arm provided with a shell-extractor and actuating-spring, an extractor-lifter, E, located at the joint of the 85 fire-arm and provided with a finger, g, a hole, k, and a circular groove or countersink, h, in one side thereof, and an opening, j, connecting said groove with the edge of the lifter, and the actuating-spring G, contained within the 90 groove h and having one end enlarged, and extending through the opening j and projecting beyond the edge of the lifter at one point, substantially as shown and described, and for the purpose stated.

JOHN C. HOWE.
